US0D1107234S

(12) **United States Design Patent** (10) **Patent No.:** **US D1,107,234 S**
(45) **Date of Patent:** **** Dec. 23, 2025**

(54) **MEDICAL IMAGE APPARATUS**

(71) Applicant: **JPIHealthcare. CO., LTD.**, Seoul (KR)

(72) Inventors: **Kyong Woo Kim**, Jeonju-si (KR); **Jin Guk Kim**, Seoul (KR); **Eun Kyu Park**, Seoul (KR)

(73) Assignee: **JPIHealthcare. CO., LTD.**, Seoul (KR)

(**) Term: **15 Years**

(21) Appl. No.: **30/000,022**

(22) Filed: **Apr. 18, 2025**

Related U.S. Application Data

(63) Continuation-in-part of application No. 29/871,939, filed on Mar. 2, 2023, now abandoned.

(57) **CLAIM**

The ornamental design of a medical image apparatus, as shown and described.

DESCRIPTION

FIG. 1 is a perspective view of a medical image apparatus showing the claimed design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof;

FIG. 9 is another perspective view thereof; and,

FIG. 10 is another perspective view thereof.

1 Claim, 10 Drawing Sheets
